FRACTIONATOR CONTROL

Joseph E. Storment, Bartlesville, Okla., assignor
to Phillips Petroleum Company, a corporation
of Delaware

Application February 23, 1942, Serial No. 432,094

1 Claim. (Cl. 196—141)

This invention relates to a method and apparatus for the control of the endpoint of distillates produced by fractionation, and more particularly it relates to a method and apparatus for the continuous control of the endpoint of overhead distillates produced by fractionation, and independent of the fractionating tower temperature and pressure.

It is well known that petroleum oils consist of mixtures of many hydrocarbon compounds some of whose boiling points lie very close together. Those compounds having similar boiling points ordinarily have similar vapor pressures, and in case a petroleum oil, or fraction or product thereof contains hydrocarbons having similar boiling points in about the same proportions, the partial pressures of these compounds will likewise be similar. Due to the effect of partial pressures it is difficult to separate the different products or fractions, each containing a number of different hydrocarbons, from each other by distillation, since a small part of the hydrocarbons whose boiling points are higher than the temperature of distillation, usually distill over with the lighter hydrocarbons, while a small part of the lighter material remains in the heavier residue. It is important that this "overlapping" of fractions be reduced to a minimum since the market value of a product is affected by the presence therein of hydrocarbons, lighter or heavier than those belonging in such fraction. For this reason a close control is kept on the fractionator products and this is ordinarily done by determining the boiling range, or initial boiling points and endpoints of test samples in the laboratory at one or two hour intervals. If these tests show that the "cut" between adjacent fractions is not sufficiently sharp, operating temperatures and/or pressures are accordingly altered in an attempt to obtain closer fractionation. In view of the time consumed in sampling a product and carrying out the distillation test, there is a considerable time lag in this method of intermittent control and it is one object of my invention to devise apparatus and a method for continuously controlling the endpoint of volatile overhead distillates produced by fractionation.

Another object of this invention is to furnish a method for the continuous control of the endpoint of volatile overhead distillates by the continuous control of liquid reflux independent of the top tower temperature and pressure.

Still another object of this invention is to furnish a practical and operable method for the continuous control of the endpoint of volatile over-

head distillates by the continuous control of liquid reflux independent of top tower temperature and pressure and with essentially no time lag in the operation.

5 Still other objects and advantages will be apparent to those skilled in the art from a careful study of the following disclosure.

By the use of my system of control such variables of operation as changing ratios of fixed gas 10 to feed, etc., are eliminated from the control system. At the present time reflux to a fractionating column may be controlled by either the top tower temperature or the pressure, or both. Thus when changing quantities of fixed gas or 15 other tower variables are encountered, a sample of the overhead stream being controlled, has to be sent to the control laboratory for analysis with a subsequent time lag before operations can be altered and "lined out" again. My means of 20 control tends to reduce this upsetting of tower operation.

The figure is a diagrammatic representation of an apparatus designed for use in practicing my invention.

25 The apparatus as herein disclosed consists essentially of a small accumulator 1, a small flash chamber 2, a flow controller 3 the operation of which is controlled by the temperature measuring device 5, and heaters 4 and 6. Such auxiliary equipment as valves, etc., for purposes of simplicity, have not been shown, as well as such other apparatus as a still for use in connection with the fractionator 7.

In the operation of the apparatus according to 30 my invention, overhead vapors from the tower 7 pass through line 8, condenser 9, and the condensate therefrom passes into the reflux run storage tank 10. A small portion of this condensate stream bypasses the said run storage 35 tank 10 and enters the small accumulator 1. The amount of condensate entering this accumulator is controlled by valve 11 and in normal operation this amount is small as compared to the portion of the stream passing to the reflux storage. Ex- 40 cess fixed gas is flashed from the small amount of condensate entering the accumulator through gas line 12. The bottoms or liquid remaining in this accumulator is transferred at a definite and uniform rate into the chamber 2, and this rate is controlled by pump 13. Sufficient heat is sup- 45 plied by heater 4 to cause complete vaporization of this small stream so that all vapor and essentially no liquid enters flash chamber 2. The heating element 6 is used to keep the tempera- 50 ture on the bottom of said chamber 2 sufficiently

55

high to prevent condensation at that point, and to supply sufficient heat to compensate for heat lost through the walls in the upper section of this chamber. The temperature and the amount of heat coming from this heater 6 are such as to allow condensation in the upper section of the chamber in order to assure that the vapors will not be superheated as they pass the temperature measuring device such as thermocouple 5 and yet prevent liquid condensate from reaching the chamber bottom and accumulating therein, or in other words, this heater maintains the vapors passing through said flash chamber in a "heat saturated" condition.

By operating this flash chamber 2 in the above described manner so that the vapors incoming through heater 4 are maintained in the vapor state and with no superheat, these vapors then passing thermocouple 5 are "saturated vapors" and their temperature is correlated to the end point of the distillate being controlled. As the temperature of these "saturated vapors" increases above a predetermined temperature the control mechanism 14 operates to open flow control valve 3 thereby permitting more reflux under pressure from pump 16 to enter the tower 7. When the temperature of the said "saturated vapors" decreases below a given temperature, the control mechanism 14 causes controller valve 3 to close partially, thereby decreasing the amount of reflux entering said tower, this decrease resulting in an increase in endpoint of the overhead stream.

The vapors from the flash chamber 2 issuing through line 15 may be condensed and disposed of as desired. The pressure in this flash chamber 2 is held constant by either automatic or manual control, the actual pressure maintained thereon being more or less immaterial.

The heaters 4 and 6 may be steam heaters, or electrical heaters, as desired, but I have found electrical heaters to give excellent results due to their ease of control.

The control apparatus, that is, thermocouple 5, regulating device 14, and flow controller 3, may well be pieces of standard equipment of conventional and well known design.

In the operation of my process, the regulation of the flow of reflux may be manual or automatic, as desired, if automatic 5 is a thermocouple, 14 is an automatic thermo-control device such that upon increase or decrease in temperature of the heat saturated vapors in the flash chamber 2 as measured by the thermocouple 5, the opening of the flow controller valve 3 is increased or decreased which change increases or decreases the flow of refluxing agent into the fractionator. The regulating device 14 may be recording or not, as desired.

If it is desired to control the flow of reflux manually, then numeral 14 represents a continuous temperature recording device. As this device then records temperatures, the operator may observe temperature changes and adjust controller valve 3 to increase or decrease the flow of reflux into the tower as desired, in which case 3 is just an ordinary valve.

Applicant does not wish to limit his invention to the use of the condensed overhead product as the reflux material added back to the tower since numerous materials may be used for this purpose. In addition, the refluxing may be of the open or "wet trim" type in which overhead product, side stream or even water in relatively small quantities may be added directly to the top of the fractionating tower and the cooling effect of this reflux addition causes condensation of the higher boiling vapors and therefore controls the end point of the effluent overhead vapors.

Refluxing as herein intended includes also the closed coil or "dry trim" type in which the refluxing material circulates through closed coils in the top of the fractionating tower in order to control the end point of the vapors passing over said coils and from the tower as overhead product. Water, condensed and cooled overhead product or other product stream may be circulated through these closed coils for refluxing purposes in which operation the amount of reflux circulated is controlled by the temperature of the heat saturated vapors passing the herein described flash chamber 2, and by such control the endpoint of the overhead vapor stream is controlled.

In some cases it may be desirable to employ wet trim and dry trim refluxing simultaneously 30 in an effort to control overhead endpoints more efficiently, and in such cases this combined or double refluxing is intended to be included within the scope of applicant's invention as herein disclosed.

35 Applicant does not wish to limit his invention to the one fully discussed embodiment since the several types of refluxing, and other alterations and variations obvious to those skilled in the art come within the intended scope of my invention.

40 What I claim is:

In the fractionation of volatile hydrocarbon mixtures in which the fractionator is refluxed, a method for controlling the end point of the fractionator overhead product substantially independent of varying quantities of fixed gases comprising condensing at least a portion of the overhead from said fractionator, removing excess fixed gases from the liquid condensate, vaporizing the liquid condensate and passing the vapors through a flash chamber, heating the lower portion of said flash chamber sufficiently high to prevent condensation of liquid at the bottom but regulating the temperature and amount of heat to allow condensation in the upper portion of said chamber, thereby maintaining the vapors in a heat saturated condition while passing through said flash chamber, and measuring the temperature of the heat saturated vapors and controlling the amount of reflux added to the fractionator by any changes in temperature of the heat saturated vapors, wherein upon increase of the temperature of the said heat saturated vapors, the reflux addition is increased, and upon decrease of the temperature of the said heat saturated vapors, the reflux addition is decreased.

JOSEPH E. STORMENT.
